UNITED STATES PATENT OFFICE.

DANIEL T. GLACKIN, OF CHICAGO, ILLINOIS, ASSIGNOR TO UNDERWOOD TYPEWRITER COMPANY, OF NEW YORK, N. Y., A CORPORATION OF DELAWARE.

TYPE-WRITING MACHINE.

1,235,792.

Specification of Letters Patent.

Patented Aug. 7, 1917.

Application filed May 18, 1917. Serial No. 169,426.

To all whom it may concern:

Be it known that I, DANIEL T. GLACKIN, a citizen of the United States, residing in Chicago, in the county of Cook and State of Illinois, have invented certain new and useful Improvements in Type-Writing Machines, of which the following is a specification.

This invention relates to typewriting machines and more particularly to machines of the fan-fold type; such, for instance, as shown in the patent to L. A. Wernery and Jesse A. B. Smith, No. 1,132,055, of March 16, 1915.

In this type of machine the interposed carbon sheets are carried by arms, and these arms extend into the open sides of the longitudinal web folds. The carbon sheets are advanced intermittently to successive fresh portions of the web. The web is usually perforated at the fold, so that a part thereof may be severed when desired. To prevent the web from being damaged by the free end of the carbon-carrying arm, a straightener is provided on said end, which engages and straightens out any irregularities that may exist in the folded portions of the web, when the carbon sheets are being repositioned.

It is sometimes the practice to provide the web with marginal perforations, so that the severed sheets may be used in loose-leaf binders. This perforating, however, causes the folded-over portion or leaf of the web to be uneven and irregular; so much so, that it is liable to become damaged by reason of the perforations catching on to the carbon-carrying arm that is arranged above or below the perforated part, when said carbon-carrying arm is being moved along the web.

To prevent the web from being thus caught and damaged, the present invention provides a deflector connected to the carbon-carrying arm. The deflector extends rearwardly, so as to be in advance of the carbon-carrying arm during the shifting of the latter along the web, and has a rounded and thinned or beveled deflecting portion which engages the web beyond the perforated margin. The deflector gradually rises or increases in thickness toward its base or mount on the carbon-carrying arm, and thus forms a slope which deflects the web over and away

from the carbon-carrying arm as the carbons are being repositioned.

Other features and advantages will hereinafter appear.

In the accompanying drawings,

Figure 1 is a perspective view of a portion of a fan-fold machine, showing my invention applied thereto.

Fig. 2 is also a perspective view, showing the carbon holding arm with a web straightener at one end of the carbon-carrying arm, and also my deflector at the other end of said carbon-carrying arm.

Fig. 3 is a top plan view of a portion of a carbon-carrying arm, showing the manner in which the webs having perforations at the sides, are deflected over the carbon-carrying arm.

Types 10 strike upwardly and rearwardly against the front of a platen 11 to make impressions on a fan-folded work-sheet 12, between the folds of which are arranged carbon sheets 13. Each of the carbon sheets 13 is attached to a reciprocating carriage 14, which is drawn forwardly upon its frame 15 by the movement of the platen, as the sheets pass around the same in line-space direction.

The carbon sheets are attached to the carriage 14 by means of blade-like bars or arms 16, which are removably attached to the reciprocating carriage by pins 16^a which extend into holes in the frame of the carriage 14. Each of the carbon sheets 13 is held to its arm 16 by being wrapped around a blade 17 and then secured by means of a clamp 17^a pivoted to the carbon-carrying blade 17.

The fan-fold web 12 is usually provided with lines of perforations 18 at its folds, so that the several parts thereof may be easily separated after a form has been written upon and detached.

After the writing of a form has been completed, the carbon sheets 13 are repositioned or advanced to a fresh portion of the web, by moving the carbon-carriage 14 with its carbon-carrying arms 16 rearwardly.

To prevent the web from liability of being damaged by the free end of the carbon-carrying arms 16, as the arms are moved to new positions, the free end of each arm 16 is provided with a straightener 19 in the form

of a flat sheet-metal plate extending rearwardly from said arm, and having its outer edge 20 inclined inwardly and rearwardly from the end of the arm, so that said end 5 20 will gradually engage and straighten the web before the irregular portion can reach the abrupt edge of the carbon-carrying arm 16.

When using fan-fold webs having binding 10 perforations at some of their folded portions, it has been found, that the web thus made uneven or irregular, is liable to become damaged by the carbon-carrying arm 16, as explained. A deflector 21 is therefore provided on each carbon-carrying arm 16. This deflector 21 is arranged at the inner or fixed 15 side of the carbon-carrying arm 16, and may be mounted directly upon the pivoted clamp 17^a. The deflector or guide 21 extends rearwardly from the carbon-carrying arm, and is rounded and thinned at its rearward extremity 22, and has a sloping portion 25 which safely guides any of the corners 23 or other irregularities formed on the web 12 by 20 the perforations 24 over the carbon-carrying 25 arm 16.

It will be noted that the deflector 21, being mounted on the inner or fixed side of the carbon-carrying arm 16, comes in contact 30 with two folded portions of the web, one above and the other below. The guide 21 is therefore provided with two sloping portions 25, one for guiding the upper portion of the web over the top of the carbon-carrying arm 16, and the other for guiding the lower portion of the web under said carbon-carrying arm. The guide 21 in this way prevents either the upper web or the lower web from fouling on the abrupt edge of the 35 40 carbon-carrying arm.

The thinned extremity 22 of the guide 21 extends into the fold of the web beyond the depth of the perforations, so that the web is first engaged at a portion where it 45 is continuous, and is then gradually lifted as the perforated portion 24 engages the guide. These perforated portions are thus lifted up on the sloping surface 25 of the guide 21, by the engagement of the web with 50 the advance extremity 22.

The guide 21 is arranged at the inner or fixed end, and the straightener 19 is arranged upon the outer or free end of the carbon-carrying arm 16, and that both the 55 deflector 21 and the straightener 19 may be used advantageously on the same arm.

The clamp 17^a, which is made of springy material, may be held to the carbon-carrying blade 17 by means of the depression 26 on 60 said clamp, which engages with an opening 27 in the carbon-carrying blade 17.

The straightener 19 may be removably held upon the clamp or spring fingers 28,

which have portions 29 adapted to frictionally hold the straightener 19 to the clamp. 65

Variations may be resorted to within the scope of the invention, and portions of the improvements may be used without others.

Having thus described my invention, I 70 claim:

1. In a typewriting machine, the combination of an arm supported at one end to carry a carbon sheet, said arm extending into the fold of a fan-folded web, a straightener on the outer end of said arm to prepare the 75 web at its folded portion for the advance of the carbon-carrying arm to a new portion of the web, and a deflector for the inner end of said carbon-carrying arm, to engage the outer portion of a perforated web fold 80 and guide the same over the carbon-carrying arm, without liability of fouling.

2. In a typewriting machine, the combination with a reciprocating carbon-retracting carriage, of arms connected at one end to 85 said carbon-retracting carriage to which carbon sheets are attached, said arms extending between the folds of a fan-folded web, and a guide for the inner or fixed end of said carbon-carrying arm for engaging the outside of the fan-folded web and guide the same over the carbon-carrying arm. 90

3. In a typewriting machine, the combination with a reciprocating carbon-retracting means, of means to which a carbon sheet 95 may be attached, and means for deflecting a work-sheet either above or below said means to which the carbon sheet is attached.

4. In a machine adapted for typewriting on work-sheets in the form of continuous 100 webs having side edge perforations therein, the combination of means for repositioning the carbon to a portion of the web following that portion which has been written upon, and means engaging the webs at the perforated side thereof for preventing the web from catching upon the carbon repositioning means at the perforated portions thereof. 105

5. In a machine adapted for typewriting upon work-sheets which are in the form of 110 continuous webs having side edge punchings therein, the combination with means for repositioning carbon sheets to a portion of the web following that portion previously written upon, and means engaging the webs at the 115 punched sides thereof for guiding portions of the web above and beneath the means for repositioning the carbon sheet.

6. In a machine adapted for writing on work-sheets in the form of a continuous web 120 having irregular margins, the combination of means extending between the webs, and means engaging the web within the irregular margins for preventing the web from catching on the means extending between the 125 webs.

7. In a machine adapted for writing on work-sheets in the form of a continuous web having irregular margins, the combination of a carbon-carrying arm extending between the webs, and a guide engaging the web within the irregular margins of the webs for preventing the web from catching on the carbon-carrying arm, said guide being thinned at its advance extremity and in- creasingly thicker toward the carbon-carrying arm, whereby the web is guided above or below the carbon-carrying arm. 10
